UNITED STATES PATENT OFFICE.

JOE VAN ECKER, OF CHICAGO, ILLINOIS.

DESIGN FOR A HAIR COMB.

Application filed June 16, 1924. Serial No. 9,877. Term of patent 3½ years.

To all whom it may concern:

Be it known that I, JOE VAN ECKER, a citizen of the United States, and a resident of Chicago, county of Cook, and State of Illinois, have invented a new, original, and ornamental Design for Hair Combs, of which the following is a specification, reference being had to the accompanying drawings, forming part thereof.

In the drawing:

Fig. 1 is a view in side elevation of a hair comb, showing my new design.

Fig. 2 is an edge view of the same as looked at from the toothed edge thereof.

I claim:

The ornamental design for a hair comb, as shown.

JOE VAN ECKER.
